(57) **CLAIM**

We claim the ornamental design for a connector housing, as shown and described.

DESCRIPTION

FIG. 1 is perspective view of a connector housing showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken line portion of the figure drawings is included for the purpose of illustrating environment and forms no part of the claimed design. Only shaded areas shown in the drawing views are part of the claimed design.
